UNITED STATES PATENT OFFICE

2,473,428

KEY HOLDER

Irving Herriott, Chicago, Ill., assignor of one-half
to David M. Davis, Oak Park, Ill.

Application June 20, 1945, Serial No. 600,432

1 Claim. (Cl. 150—40)

1

This invention relates to keyholders, and more particularly to keyholders of the book type in which a cover is provided over an arrangement which holds the keys accessible for ready selection and for ready insertion or removal from a cooperating lock.

It is an object of this invention to provide a simplified and improved keyholder in which the keys are retained side by side for ready selection and for easy use, and particularly in which the key retaining arrangement is simple to make and easy to use and is rugged and longlasting.

It is a further object of this invention to provide such a key retaining arrangement in which the keys are held flatly one against the next and from which individual keys may be turned to project out of the cover for ready use, in which projected position the key is restrained from turning with respect to the key retaining arrangement and its cover.

The features of my invention which I believe to be novel are set forth with particularity in the appended claim. The invention itself, both as to its organization and manner of operation, together with further objects and advantages thereof, may best be understood by reference to the following description taken in connection with the accompanying drawings in which:

Figure 1 illustrates a keyholder embodying one form of my invention;

Figures 2 and 3 illustrate certain parts of the device shown by Figure 1 before such parts are assembled;

Figure 4 shows an alternative form of the part shown in Figure 2;

Figure 5 shows still another alternative form of the part shown in Figure 2; and

Figure 6 is an assembled view of the alternative parts shown in Figure 5.

In Figure 1 a cover 10, which may be made of leather, impregnated fabric, or the like, supports a key fastening device 11, which may suitably be made of resilient metal or plastic. The device 11 includes a flat rectangular base portion 12 which is fastened, as illustrated, to cover 10 by suitable means such as two flat headed rivets 13 and 14. Formed integrally with the base 12 there is an upstanding part 15, preferably of the same width as base 12. The part 15 is also formed integrally with a long, thin tongue 16 which extends back over the base 12 to a point a little beyond its opposite end.

On that opposite end of base 12 there is formed integrally an upstanding latch portion 17. The tongue 16 is small enough in cross section to pass through the hole usually provided in the handle part of a key 18. This tongue 16 is so shaped that its resilience, together with that of the upstanding part 15 and base 12, tends to force its free end some distance away from the latch 17.

2

in which free position keys may readily be threaded upon, or removed from, tongue 16. When keys 18 are arranged on tongue 16 in the desired order and position, tongue 16 is depressed against its resilience toward base 12 and into the latching position in latch 17.

With keys 18 thus arranged as desired on tongue 16 and with the tongue latched in place, cover 10 is closed over the keys and the free edges of cover 10 are fastened together by suitable means, such as the complementary snap fasteners 19 and 20. When it is desired to use one of the keys 18, the cover 10 is opened, the desired key 18 is turned out of the cover in an upward direction, and the cover 10 is again snapped closed, leaving the key 18 projecting outwardly ready for use and restrained against turning by engagement of tongue 16 through the hole in the key handle.

In Figure 2 the key fastening device is illustrated as it appears during one step of its manufacture. The construction and operation of latch 17 are clearly indicated. This illustrated part may, if made of metal, be readily stamped in a single operation from a flat blank to form

the tongue 16, the part 15, base 12 and latch 17 all lying in one plane. If made of plastic, it may be molded in the shape illustrated. After such stamping or molding, the device is bent substantially at right angles at three places, illus-

trated by dotted lines 21, 22 and 23. Dotted line 21 illustrates where the bend is formed between base 12 and part 15. Dotted line 22 illustrates where the bend is formed between part 15 and tongue 16. Dotted line 23 illustrates where the

bend is formed between base 12 and latch 17. If the device 11 is metal, these bends may readily be made by stressing the metal beyond its yield point; or if the device 11 is plastic, the bends are preferably made by the application of heat and

pressure to shape the material to the desired bent form, the plastic being of a composition suitable for such treatment.

The latch 17 has two snap latch members 24 and 25 in which there are formed respectively oppositely facing notches 26 and 27. When tongue 16 is pressed into latch 17, the snap latch members are forced slightly apart and tongue 16 snaps into notches 26 and 27 in which it is retained until forced out by the application of suitable pressure. The notches 26 and 27 are shaped to wedge apart the members 24 and 25 when tongue 16 is forced out of its latched position in those notches.

In Figure 3 the cover 10 is shown as it appears in one step of its manufacture. It, like device 11, may be stamped or die cut, from suitable flexible material, in a single operation, and is folded along dotted lines 28, 29, 30, and 31 to cover the device 11 and keys 18 held thereon.

The base 12 of device 11 is provided with holes

32 and 33, and cover 10 with complementary holes 34 and 35 through which rivets 13 and 14 are fastened.

Cover 10 is also arranged to fold along the dotted lines 28, 29, 30 and 31 so that its free edges and the snap fasteners 19 and 20 come together in such a way that the snap fasteners hold cover 10 over device 11 and keys 18 in the shape of a wedge. Since keys are usually tapering and thin toward the end which engages a lock and are necessarily wider at the handle end, the wedge shaped cover 10 nicely covers the keys held on device 11 and leaves no unnecessary space within the key holder.

This form of the invention is of especial advantage since it requires only two major parts: device 11 and cover 10—each of which is made in a simple die stamping operation, and since, in addition to those two major parts, it includes only two rivets and two complementary snap fastener parts, all of which is assembled in a simple operation. The device as a whole is therefore simple in the extreme and is consequently cheap and easy to make, while at the same time it is so arranged that it is simple and easy to use.

In Figure 4 an alternative form of the latch part of device 11 is illustrated, in which the base 12 is formed integrally with a hook latch 36. The hook 36 has a leg 37 integral with base 12 and extending into a cross part 38 with a depending tongue 39 to form a recess 40 into which tongue member 16 may be latched.

If this alternative latch 36 be used, it is preferred that tongue 16 be not only shaped and bent to spring away from base 12 but also that it be bent somewhat toward the upper edge of base 12 so that the resilience resulting from both such bendings forces tongue 16 into recess 40 and toward leg 37, the better to retain the tongue 16 in the latch 36.

In Figure 5 an alternative form of device 11 is illustrated, in which a base 41 is formed integrally in a single stamping or molding operation with projecting bearing members 42 and 43 on one end, and with a pair of snap latch members 44 and 45, like members 24 and 25 in Figure 2, on the other end. Notches 46 and 47 are formed in the same operation in snap latch members 44 and 45 and simultaneously holes 48 and 49 are formed in base 41 for the reception of rivets 13 and 14. Also in the same stamping or molding operation a tongue 50, similar in shape to tongue 16, is formed integrally with bearing pins 51 and 52 extending at right angles to one end of tongue 50. Of course, since the tongue 50 in this form of the invention is a piece separate from the base 41, it may, if desired, be formed in a separate stamping or molding operation, but it is preferred to use a single die to cut both parts at one time in order to reduce the cost of dies and of machines on which the dies are operated.

After those two parts are thus formed, the snap latch members 44 and 45 are bent up at right angles to base 41 and bearing members 42 and 43 are also bent up at right angles to base 41 along dotted line 53 and on the same side of base 41 as snap latch members 44 and 45. The bearing members 42 and 43 are also rolled around the bearing pins 51 and 52 to form a bearing between tongue 50 and base 41, so that tongue 50 may be depressed toward base 41, whereupon its free end is engaged and locked in the oppositely facing notches 46 and 47 in the adjacent edges of snap latch members 44 and 45. Pressure

against tongue 50 away from base 41, the distance between snap latch members 44 and 45 being just right to require suitable pressure, disengages tongue 50 from notches 46 and 47 and allows the loading of keys on tongue 50 or the removal of keys therefrom, all in a fashion similar to the operation of latch 17 in Figure 1.

Figure 6 illustrates the parts shown in Figure 5 after their assembly. Like reference numerals are applied to parts like those illustrated in Figure 5. The bearing 43, 52 provides a hinge for tongue 50 on base 41, so that the tongue may be moved freely with respect to base 41 except when it is snap engaged in notches 46 and 47 of snap latch members 44 and 45.

This form of the invention, like that of Figure 1, has an advantage in that pressure exerted through cover 10 upon the keys and hence upon tongue 50 tending to depress it toward base 41 acts only to engage tongue 50 more firmly with snap latch members 44 and 45.

It is within the scope of my invention to utilize the latch 36 instead of members 44 and 45 with the device shown in Figures 5 and 6.

While I have shown and described certain particular embodiments of my invention, it will be obvious to those skilled in the art that changes and modifications may be made without departing from my invention in its broader aspects, and I, therefore, aim in the appended claim to cover all such changes and modifications as fall within the true spirit and scope of my invention.

I claim:

A key holder comprising: a key fastening device having a flat base portion, an upstanding portion formed integrally with said base portion, a resilient tongue member formed integrally with said upstanding portion and extending substantially parallel to said base portion, and an upstanding latch portion formed integrally with said base portion at an end thereof opposite said first mentioned upstanding portion and constructed to engage the end of said tongue member remote from said first mentioned upstanding portion; a wedge-shaped covering member having a relatively large end and a relatively small end; a first side openable to admit access to keys carried by said device; and a second side including means for securing said base portion to said second side along a transverse axis of said second side adjacent said large end; said tongue member being spaced a predetermined distance from said base portion to permit the carrying of a plurality of keys slidably and rotatably on said tongue member; whereby, when stored, said keys lie with their handles at said large end and their narrow lock-engaging portions extending towards said small end, and when selected for use said keys are rotatable to a position with their lock-engaging portions extending outside said cover at said large end.

IRVING HERRIOTT.
